E. P. EDSTROM, OF SOMERVILLE, MASSACHUSETTS.

Letters Patent No. 70,079, dated October 22, 1867.

IMPROVEMENT IN THE MANUFACTURE OF HORSE-COLLARS.

The Schedule referred to in these Letters Patent and making part of the same.

TO ALL WHOM IT MAY CONCERN:

Be it known that I, E. P. EDSTROM, of Somerville, in the county of Middlesex, and State of Massachusetts, have invented certain new and useful improvements in the Manufacture of Horse-Collars; and I do hereby declare that the following, taken in connection with the drawings which accompany and form part of this specification, is a description of my invention sufficient to enable those skilled in the art to practise it.

The invention relates to the construction of horse-collars, and particularly to the manner of forming the roll or rim, which, in connection with the body, forms the bed and groove for the application of the hames.

In the common construction of horse-collars it is customary to first form the outer material or covering of the roll into a tube, and to then stuff such tube with a filling of straw or other similar material. Such construction is for many reasons objectionable, and I have of late devised, to take the place thereof, a roll in which a core is first formed of the general shape of the collar, over which core the leather to form the roll is drawn and stitched, and it is in such method or process of forming the roll that my present invention consists.

In carrying out my invention I prefer to employ a series of blocks, such as are shewn in the drawings, my method of procedure being as follows:

I first take a piece of rattan, or other suitable flexible or somewhat flexible and elastic material, and, having cut it to the proper length and reduced it to the proper thickness and form, as seen at *a*, I shave down the ends, and fasten upon them strips of leather *b*, and then bend the core-piece and secure the two ends of leather together, as seen at *c*. The piece *a*, which is in a wet or somewhat soft condition, I then place upon the block *A*, said block having a bed-face, *d*, against which the piece *a* lies, and a former, *e*, of the general outline or shape which it is desired that the collar may have. The point-piece *f* of the former slides outwardly in the block, and the piece *a*, being laid around the former as seen at *A*, a wedge is driven between the piece *f* and the main former-block *e*, till the wood or other material *a* lies closely against the edge of the pattern-block *e* all along its length, in which position it is left to dry. Being then removed, this piece retains its shape, and forms the core upon which the roll is to be formed. A face view of the core upon the former-block is shown at *A*, and a cross-section of the core and block at *B*. I next take this core and stretch it upon the block *C*. This block also is made in two parts, in the edge of which is sunk a groove, *g*, as seen at *D*, which shows a section of the block and core, and the core being slipped upon the block and into the groove, the pieces *h* are wedged apart to strain the core upon the block to hold it firmly in place. Through a hole, *k*, I clamp the block to the side of a bench in upright position, or so that I may rotate it upon the screw or clamp-pin. I then stretch over the outer surface of the core the central part of a strip of leather, which is to form a lining to the outer or face-leather of the roll, this lining being first laid over the core, and the face-leather over it.

Having the lining-leather wet, and while in a pliant condition, I tack one end of it to the top of the core, and stretch it gradually over the outer surface of the core, turning the block as I proceed, so that when the core is removed from the block, and the lining is drawn around it, the outer part of the strip shall be so stretched that the part which goes within the core shall not pucker. This being effected, I stretch over this lining-leather the outer leather in the same manner, and for the same purpose of making it lie smoothly upon the inner as well as on the outer surface of the core when finished. Previously to such manipulation these pieces are cut to the proper length, and of a width sufficient to leave opposite projecting edges upon each when they are applied to the core, something as seen at *E*, the edges of the lining piece projecting out beyond the edge of the face-leather, which is cut narrower than the lining. In this position they are basted together, the thread running through the four edges. The roll so covered, I lay upon a third block, *F*, seen in section at *G*, and stitch to it the body-leather *l*, the face side of which at the inner edge is laid against the inner one of the edges of the roll-leather previously basted together, and the five are then stitched tightly together, during which operation the shape of the block *G* allows the wide body-leather to fall down into its hollow *m*, so as to leave free room for the stitching, and for the body-leather to be laid smoothly along the roll, which would not be the case were the roll placed on a bench, held in the lap, or placed on the floor. The inner body-leather having been thus applied, it is turned over, the outer piece is connected to it, and the body is stuffed in the usual manner.

In the manufacture of key-collars, or that class of collars in which the part of the body within the collar is extended over and so as to form part of the roll, I stitch this body-piece and the outer rim or face-piece

together before placing them on the roll, and I then apply the collar, with the inner or lining part applied thereto, to a block, H, having a wide groove, n, and draw on and secure the outer covering while the collar is upon such block H, the width of the groove *n* permitting the inner surface of the roll and body to fit therein, and this block H being used as an auxiliary to the other blocks.

I claim the improvement in the manufacture of horse-collars by forming a core, and applying thereto the roll and body-leather upon a system or series of blocks, substantially as set forth.

E. P. EDSTROM.
